UNITED STATES PATENT OFFICE

2,452,668

TOY GUN

George P. Lee, Stroudsburg, Pa.

Application March 17, 1944, Serial No. 526,940

1 Claim. (Cl. 124—27)

1
This invention relates to toy guns, and more particularly to toy guns adapted to project various types of projectiles such as toy parachutes, arrows or the like.

An important object of the invention is to provide a toy gun of this character embodying a multibarrel structure including a pivoted barrel adapted to be moved to various angular positions with respect to the main gun barrel, to the end that projectiles may be discharged from the barrels at various angles, with a single operation of the trigger, thereby providing a toy which is exceptionally amusing and fascinating.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawing:

Figure 1 is a longitudinal sectional view through a gun, constructed in accordance with the invention, the pivoted gun barrel being shown at an oblique angle with respect to the main gun barrel.

Figure 2 is a plan view thereof.

Figure 3 is a sectional view taken on line 3—3 of Fig. 1.

Referring to the drawing in detail, the main section of the toy gun embodies a barrel 5 and a handle 6 formed at one end thereof. The barrel 5 is formed with a bore 7 in which the spring-pressed plunger 8 moves, the spring-pressed plunger 8 being engaged by the coiled spring 9 which is mounted within the bore between the inner end of the bore and plunger. A flexible connecting member 10 connects with the plunger 8 and is secured to the trigger 11 that is pivotally connected to the barrel 5, as clearly shown by Fig. 1 of the drawing, the connection between the flexible connecting member 10 and trigger, being made at a point below the pivot point of the trigger 11.

A coiled spring indicated by the reference character 12 has one end thereof anchored to the underside of the barrel 5, at 13, the opposite end thereof being connected to the trigger 11 near the lower end thereof. The spring 12 is of the contractile type, so that when the lower end of the trigger is moved rearwardly, the spring is tensioned to return the trigger to its normal position when released.

2

Pivotedly mounted on the outer end of the barrel 5, is the barrel 14 which is connected with the barrel 5 in such a way that friction will be set up between the barrel 14 and barrel 5 to hold the barrel 14 in various positions of adjustment with respect to the barrel 5.

The bore of the barrel 14 is indicated by the reference character 15 and accommodates the plunger 16, there being a coiled spring 17 disposed between the plunger 16 and rear end of the bore 15, so that when the plunger 16 is moved rearwardly, or to the position as shown by Fig. 1 of the drawing, the spring 17 is compressed to extend the plunger 16 towards the open end of the barrel to project the article positioned therein.

Connected with the plunger 16 is a flexible member 18 that moves under the eye bolt 19 and has its looped end fitted in a notch of the trigger 11. Thus it will be seen that when projectiles are positioned in the barrels, and the plungers are in their positions as shown by Fig. 1 of the drawing, it is only necessary to pull the lower end of the trigger 11 rearwardly towards the handle 6, whereupon the plunger 16 will be released to the action of the coiled spring 17, the article held within the barrel being projected. Upon releasing the trigger 11, the coiled spring 9 which has been tensioned by the rearward movement of the trigger, will cause the plunger 8 to be extended towards the open end of the barrel 5, projecting the article. Thus it will be seen that various types of projectiles, such as a toy parachute and toy arrow, may be projected with one operation of the trigger, the projectiles passing from the gun in different directions, and providing an exceptionally amusing and attractive toy.

What is claimed is:

A toy gun comprising a main gun barrel, a gun barrel pivotally connected to the main gun barrel and adapted to be adjusted to various angular positions with respect to the main gun barrel, plungers operating in the barrels, springs within the barrels adapted to normally urge the plungers outwardly, a trigger pivotally mounted on the main gun barrel, a flexible member connected with the plunger operating within the pivoted gun barrel, and being releasably connected to said trigger at a point above the pivot point of the trigger, a flexible member connected with the plunger of the main barrel and being connected with the trigger at a point below the pivot point of the trigger, a control spring connected with the main gun barrel and being connected with the trigger at a point below the pivot point of the trigger, and adapted to normally urge the upper end

of the trigger rearwardly against the action of the spring in the pivoted barrel, and said trigger adapted to release the spring in the pivoted barrel and simultaneously tension the control spring and spring in the main gun barrel, when the trigger is moved rearwardly, and the spring in the main gun barrel adapted to eject an article from the main gun barrel when the trigger is released.
